UNITED STATES PATENT OFFICE.

DIEDRICH H. SPRECKELS, OF DEXTER, MINNESOTA.

POULTRY-CRATE.

1,329,344.

Specification of Letters Patent. Patented Jan. 27, 1920.

Application filed March 27, 1918. Serial No. 225,059.

To all whom it may concern:

Be it known that I, DIEDRICH H. SPRECKELS, a citizen of the United States, residing at Dexter, in the county of Mower and State of Minnesota, have invented certain new and useful Improvements in Poultry-Crates; and I do hereby declare the following to be a full, clear, and exact description of the invention, such as will enable others skilled in the art to which it appertains to make and use the same.

The present invention comprehends generally improvements in that class of inventions known as wooden receptacles and more particularly relates to an improved crate.

It is the primary aim and object of the present invention to provide a device of the above mentioned character designed for holding fowls, such as chickens, the construction thereof being novel in form to enable the owner to readily remove a desired chicken therefrom, without allowing others to escape.

More particularly the present invention contemplates the provision of a device of the above mentioned character wherein a partition is mounted transversely in the body for longitudinal movement and is designed to divide the body into two compartments, when held stationary, or when moved act as an ejector and a cleaner for the crate, as desired.

As a further improvement this invention consists in the provision of a crate of the above mentioned character wherein a handle of a novel form is employed for either sliding the partition or for holding the same stationary.

Among the other aims and objects of this invention may be recited the provision of a device of the character described with a view to compactness, and in which the number of parts are few, the construction simple and the cost of production low and the efficiency high.

Other improvements and novel details in the construction and arrangement of the various parts of the apparatus will be brought out more in detail in the description to follow, which for a clear understanding of the invention should be considered in connection with the accompanying drawings forming a part hereof, and wherein is disclosed for the purpose of illustration a convenient and satisfactory embodiment of the invention. It is to be noted in this con-

nection that minor changes may be made without departing from the principle of operation of the various parts.

The invention is clearly illustrated in the accompanying drawings, in which:

Figure 1 is a perspective view of the device,

Fig. 2 is a longitudinal central section thereof, and

Fig. 3 is a transverse section taken on line 3—3 of Fig. 2.

Similar characters of reference are employed in all of the above mentioned views, to indicate corresponding parts.

Referring now, more particularly, to the accompanying drawings there is provided a crate the body of which is desirably of a rectangular configuration and comprises a bottom 1 to the respective ends of which are connected end walls 2, having door openings 3 therein, while opposed side walls 5 and a top 4 are connected to the corresponding outer edges of the end walls 2. The top and side walls may be composed of spaced slats 6, as desired. Doors 7 are pivotally connected such as by hinges 8 to the end walls and are designed to close the openings 3, being held in a closed position by suitable fasteners 9.

As intimated, improved means have been provided for dividing the crate into compartments and for serving as an ejector and a cleaner for the crate. In reducing this feature of the invention to practice, a partition 10 which may be of substantial rectangular configuration to conform to the end walls is slidably mounted within the body of the crate and arranged in close relation with the adjacent inner surfaces thereof for longitudinal movement therein.

With a view to providing improved means for either holding the partition stationary to divide the body of the crate into two compartments, or actuating the partition so as to eject the fowls or serve as a cleaner, a handle is employed and consists of relatively movable sections 11 and 12 which may be and desirably are of rectangular configuration, being pivotally connected to each other by means of a hinge 13, the leaves of which are connected to the upper surfaces and near the adjacent ends of the sections, as indicated in the drawings. The inner section 11 of the handle has the inner end thereof secured in a recess 14 in the lower edge of the partition so as to lie flush therewith while

both the inner section 11 and the outer section 12 of the handle are slidable through a recess 15 in the lower edge of one of the end walls and this recess of course alines with 5 the recess 14 to permit of free sliding movement of the handle longitudinally of the body of the crate. In this connection it is to be observed that when the outer section is free of the body of the crate the same is de- 10 signed to be swung upwardly when desired, and arranged against the adjacent end wall of the crate so as to retain the partition substantially medially of the end walls and thus divide the body of the crate into two com- 15 partments in which fowls may be placed for shipping, as is apparent.

In use, assuming that the parts have been assembled in the manner described and as indicated in the drawings, especially in Fig. 2, when it is desired to remove a certain chicken from the body of the crate, the outer section 12 of the handle is engaged and swung downwardly to register with the recess 15, which provides an opening, where- 25 upon the handle is either moved in the direction toward the forward end wall or toward the rear end wall, the partition acting as an ejector for moving the chickens in either of the compartments toward the cor- 30 responding end wall. The door of course may be partially opened and the owner may insert his arm therethrough and grasp any chicken desired. When there are no chick- 35 ens in the body of the crate, the handle may be actuated so that the partition will act as a cleaner for the bottom of the crate, as is apparent. Of course, when the parts are in the position indicated in Fig. 2, chickens or other fowl may be conveniently shipped 40 therein, the arrangement of the outer section

12 of the handle against the adjacent end wall serving to removably hold the partition in a substantially stationary position medially of the end walls of the body of the crate.

It is believed in view of the foregoing de- 45 scription, that a further detailed description of the operation of the invention is entirely unnecessary. Likewise, it is believed that the advantages of the invention will be readily apparent. 50

Having thus fully described the invention, what is claimed as new and desired to be secured by Letters Patent is:

A crate including a body having end open- 55 ings and doors for closing the same, a par- tition member fitting snugly within said body and slidable longitudinally thereof, and an adjusting member secured at one end to the partition member and slideable through one end of said body, said adjust- 60 ing member comprising two sections hinged- 65 ly secured together at their adjacent ends and each approximately one-half as long as the body whereby the partition member may be moved in either direction for substantially the full interior length of the body and, by withdrawing the adjusting member for one- half of its length and turning the outer por- 70 tion thereof upwardly against the adjacent end of the body, the partition member may be secured in adjustment at the central por- 75 tion of the body so as to divide the same into two separate compartments.

In testimony whereof I affix ~~my~~ signature in presence of two witnesses.

DIEDRICH H. SPRECKELS.
